[57] CLAIM

The ornamental design for an emergency sign for automobiles, as shown and described.

DESCRIPTION

FIG. 1 is a front perspective view of a emergency sign for automobiles, showing my new design, the rear perspective view being a mirror copy of this front perspective view;

FIG. 2 is a perspective view of a second embodiment, wherein the only different resides in the message;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a reduced rear elevational view thereof, with the broken lines showing an automobile for illustrative purposes only and forming no part of the claimed design.
